ENGINE STARTING DEVICE

Benjamin Getz and Alex Johnson, Milwaukee,
Wis.

Application July 25, 1938, Serial No. 221,147

8 Claims. (Cl. 74—9)

This invention relates to engine starting devices for internal combustion engines and more particularly to improved engine starters, although certain features thereof may be employed with equal advantage for other purposes.

It contemplates more especially an improved automatic engine starter that eliminates the use of mechanical springs and provides more dependable and effective cushioning action in the operation thereof.

In engine starters of known construction, the cushioning springs and the starter shaft are subject to severe strain, and as a result require replacement at appreciable expense. This is especially true in the type of engine starters that employ mechanical springs rather than resilient cushioning expedients of the type disclosed in United States Letters Patent No. 2,070,277 constituting an engine starter attachment. The present invention provides even an improved construction thereover and relates primarily to an engine starter rather than an attachment therefor to secure more effective cushioning action in a rotary as well as a longitudinal direction.

One object of the present invention is to simplify the construction and improve the operation of devices of the character mentioned.

Another object is to provide an improved rotary and longitudinal cushioning action in engine starters.

Still another object is to provide a novel assembly of resilient cushioning members together with mechanical instrumentalities in a self-contained engine starter.

A further object is to provide an engine starter of simple and improved construction that provides for rotary and longitudinal shock absorbing rubber cushioning expedients.

A still further object is to provide a novel assembly of instrumentalities embodying rotary and end thrust resilient cushions that are more effective and dependable in engine starter operations.

Still a further object is to provide an improved engine starter of more efficient and durable design giving rise to minimum or negligible wear on any elements thereof.

An additional object of the invention is the provision of a novel construction, arrangement and assembly of parts comprising a self-contained engine starter.

Other objects and advantages will appear from the following description of an illustrative embodiment of the present invention.

In the drawing:

Figure 1 is a sectional view in elevation of a device embodying features and teachings of the present invention.

Figure 2 is a perspective view of a disc constituting an element of the assembled structure shown in Figure 1.

Figure 3 is a sectional view taken substantially along line III—III of Figure 1.

Figure 4 is a sectional view taken substantially along line IV—IV of Figure 1.

Figure 5 is a sectional view taken substantially along line V—V of Figure 1.

Figure 6 is a fragmentary sectional plan view of a driven shaft including the pinion.

Figure 7 is a perspective view of a coupling element that cooperates with the driven shaft shown in Figure 7.

Figure 8 is a perspective view of a cushioning block retainer housing.

Figure 9 is a perspective view of a preformed rubber cushioning block constituting an element of the assembled device shown in Figure 1.

Figure 10 is a perspective view of a longitudinally slotted collar or housing constituting a part of the assembled unit shown in Figure 1.

Figure 11 is a perspective view of a preformed rubber end thrust absorbing member or disc constituting part of the assembled unit shown in Figure 1.

The structure selected for illustration comprises a starter housing 10 which has an end hub 11 merging with an enlarged peripheral shoulder 12 formed concentrically therewith to define peripheral end surfaces 13 and 14. The shoulder 12 has a rib 15 extending longitudinally of a housing bore 16 provided through the hub 11 and its peripheral shoulder 12. As shown, the rib 15 preferably though not essentially has inwardly converging surfaces 17 and 18 interposed between arcuately convex and concave surfaces 19 and 20, respectively. The arcuately convex surface 19 merges with the peripheral surface of the shoulder 12 and the correspondingly concave arcuate surface 20 extends beyond the axial bore 16 to accommodate instrumentalities as will appear more fully hereinafter.

The rib 15 merges with a circular end shoulder 21 preferably though not essentially of the same diameter as the shoulder 12, they being maintained in rigid spaced parallel relation by means of the rib 15. An axial bore 22 is provided in the end shoulder 21 for alignment with the comparatively smaller bore 16 concentrically disposed in the hub 11 and shoulder 12. A keyway 23 is

broached or otherwise provided in the bore 16 and such serves to effectively receive a starting driving shaft 24 therethrough for rotation therewith through the medium of an interconnecting key 25. The starter driving shaft 24 extends through the spaced shoulders 12 and 21 having the bores 16 and 22 provided axially therethrough, and such preferably though not essentially extends to the end surface 13 for contact with an armature shaft 26 constituting a part of the starter motor (not shown).

In order to engage the hub 11 with the armature shaft 26 for rotation therewith, a threaded stud screw 27 extends radially through the wall of the hub 11 so that its pointed set screw extremity 28 will engage a correspondingly shaped recess provided in the armature shaft 26, thereby establishing a fixed connection therebetween for rotation of the starter housing 10 responsive to the energization of the starting motor that serves to rotate the starting driving shaft 24. As shown, the starter driving shaft 24 extends beyond the end shoulder 21 of the retainer housing 10 and terminates in a reduced extremity 29 which is journaled in a bearing to support the driving shaft 24 in axial alignment with the armature shaft 26 of the starter motor (not shown).

A driven shaft 30 of tubular construction has an axial bore 31 extending therethrough for journaled rotation on the driving shaft 24. The external diameter of the tubular driven shaft 30 conforms to the diameter of the bore 22 in the end shoulder 21 of the housing 10, while the inner bore 31 conforms with the external diameter of the driving shaft 24 so as to effect the accurate and smooth running assembly between these relatively moving parts. The tubular driven shaft 30 is, in this instance, provided with an engine gear meshing pinion 32, it being integrally or otherwise attached thereto for rotation therewith in conjunction with a convolutely disposed groove engaging lug 33.

The convolutely disposed groove engaging lug 33 extends radially from the inner end 34 of the driven shaft 30, it being preferably though not essentially formed integral therewith to mesh with a convolute groove 35 formed in a sleeve 36. The sleeve 36 has its internal contour 37 conforming substantially in size with the external diameter of the driven shaft 30 for relative rotation therebetween responsive to the rotation of the driven shaft 30 to simultaneously effect its longitudinal displacement to cause the pinion 32 to engage and disengage its complemental engine gear (not shown) depending upon the comparative speed of rotation therebetween. It is to be noted that one extremity 38 of the sleeve 36 is disposed in an annular recess 39 provided in the inside surface of the end shoulder 21 for communication with the end bore 22 therein, while the other extremity 40 of the sleeve 36 is journaled on a hub 41 comprising part of a circular disk 42.

To maintain these parts in predetermined assembled relation against relative rotation therebetween, the sleeve 36 has a radially extending lug 43 formed thereon, it having an arcuate end surface 44 and radially converging side surfaces 45 and 46 to cooperate with the oppositely disposed housing key rib 15 to define circumferential spaces for a pair of arcuately preformed resilient rubber blocks 47 and 48 (Figure 5). As shown, the resilient and arcuately preformed resilient blocks 47 and 48 contact a correspond-

ingly arcuate metallic sleeve 49 that is longitudinally slotted along the length thereof as at 50 to receive the radial lug 43 of the inner sleeve 36 whose external diameter conforms with the internal diameter of the outer sleeve 49. Consequently, the inner sleeve 36 and outer sleeve 49 are maintained in assembled association against relative rotation and the arcuately preformed resilient rubber blocks 47-48 are disposed thereon between the key rib 15 and sleeve lug 43, the arcuate extent of the preformed resilient cushioning blocks 47-48 being somewhat less than the circumferential distance between the oppositely disposed key rib 15 and inner sleeve lug 43 to permit relative movement between the driving shaft 24 and the driven shaft 30 to permit the longitudinal displacement of the pinion 32 for engagement and disengagement with the engine gear (not shown).

The longitudinal displacement of the starting pinion 32 is effected by virtue of the rotation of the driving shaft 24 with the retainer housing 10 and convolutely grooved sleeve 36 relative to the shaft 30 with its lug 33 riding in the convolute groove 35. It will be apparent, therefore, that one of the arcuately preformed resilient rubber blocks 47-48 will sustain the torque load and absorb or cushion the circumferential shock when the pinion 32 engages the engine gear with which it meshes while the other cushioning block will serve to sustain the load and absorb or cushion the shock during their disengagement after the engine gear commences to rotate at a greater speed than the pinion 32. So that the end lug disc 42 will not rotate relative to the housing 10, it is provided with a notch 51 that corresponds in shape with and serves as a complement of the key rib 15 to maintain the parts in their assembled relation.

In order to absorb the end thrust that is occasioned when the starting disc 32 becomes disengaged after the engine gear has started to rotate at a greater speed than the disc 32, a preformed resilient rubber disc 52 is interposed between the end surface 14 of the housing shoulder 12 and the metallic disc 42. The preformed resilient disc 52 has an axial bore 53 corresponding in size with the diameter of the driving shaft 24 and a notch 54 is provided in the circumferential edge thereof to correspond with the notch 51 in the adjacent metallic disc 42 for alignment and registry therewith to engage the key rib 15 and preclude relative rotation with the housing 10. A notch 54' is provided in the bore 22 of the end shoulder 21 to enable the insertion of the driven shaft 30 with its lug 33 therethrough.

It will be noted that the metallic disk 42 and the circularly preformed resilient rubber disk 52 are of corresponding diameter and extend to the external arcuate surface 19 of the key rib 15 constituting an integral part of the starter housing 10. A cylindrical protective casing or sleeve 55 has its internal diameter corresponding with the external diameters of the peripheral shoulders 12 and 21 of the housing 10 so as to contact therewith and enclose the housing 10 together with the parts assembled therewith. To this end, a threaded stud 56 projects through one edge of the protective casing sleeve 55 to engage a correspondingly threaded aperture 57 in the shoulder 12 to maintain the parts in assembled relation and preclude the entry of foreign substances that would have a deteriorating effect upon the resilient rubber cushioning members 47, 48, and 52.

With the arrangement of parts above described,

it will be apparent that when the starting motor (not shown) rotates its armature shaft 26, corresponding rotation will be imparted to the housing 10 and the driving shaft 24 which will momentarily cause the driven shaft 30 to be displaced outwardly to effect meshing engagement of the pinion 32 with the engine starting gear (not shown). Thereupon, the lug 33 on the driven shaft 30 will reach the limit of movement in the convolute groove 35 to effect rotation of the pinion 32 while in meshing engagement with the engine gear, thereby starting the engine to which it is attached. In consequence thereof, the starter engine will commence to rotate at a higher speed than the normal rate of rotation of the driving shaft 24 to the end that the driven shaft 30 will recede inwardly along the convolute groove 35 and effect dis-engagement of the starting pinion 32 that momentarily was in meshing engagement with the engine gear. The starting motor is then de-energized by the driver when the engine has started its operation so as to place the component elements in their initial position for another starting operation responsive to energizing the starter motor (not shown).

A very simple, dependable and effective engine starter has been provided that is comparatively inexpensive in construction and provides a far more effective cushioning in both a circumferential and axial direction than heretofore obtainable with similar starting devices. Various changes may be made in the embodiment of the invention herein specifically described without departing from or sacrificing any of the advantages of the invention or any features thereof, and nothing herein shall be construed as limitations upon the invention, its concept or structural embodiment as to the whole or any part thereof except as defined in the appended claims.

We claim:

1. In a device of the character described, the combination with a starting driver shaft, a driven shaft telescopically mounted relative to said driver shaft, a pinion fixedly mounted for rotation with said driven shaft to engage and disengage an engine gear for starting purposes, a sleeve telescopically associated with said driven shaft, there being a screw connection between said sleeve and driven shaft, an eccentric formed on said sleeve, a retainer member associated with said driver shaft to circumferentially confront said sleeve eccentric, a pair of arcuately preformed resilient rubber means interposed between said last named member and said eccentric on said sleeve to operatively effect their connection, and an axially disposed preformed rubber member operatively interposed between said driver and driven shafts to sustain end thrusts therebetween.

2. In a device of the character described, the combination with a starting driver shaft, a driven shaft telescopically mounted relative to said driver shaft, a pinion fixedly mounted for rotation with said driven shaft to engage and disengage an engine gear for starting purposes, a sleeve telescopically associated with said driven shaft, there being a screw connection between said sleeve and driven shaft, an eccentric formed on said sleeve, a retainer member associated with said driver shaft to circumferentially confront said sleeve eccentric, a pair of arcuately preformed resilient rubber means interposed between said last named member and said eccentric on said sleeve to operatively effect their connection, an end disc fitted to said driver shaft 75

to concentrically space said sleeve relative to said driven shaft, and an axially disposed preformed rubber member disposed adjacent said end disc and operatively interposed between said driver and driven shafts to sustain end thrusts therebetween.

3. In a device of the character described, the combination with a starting driver shaft, a driven shaft telescopically mounted relative to said driver shaft, a pinion fixedly mounted for rotation with said driven shaft to engage and disengage an engine gear for starting purposes, a sleeve telescopically associated with said driven shaft, there being a screw connection between 10 said sleeve and driven shaft, an eccentric formed on said sleeve, a retainer member associated with said driver shaft to circumferentially confront said sleeve eccentric, a pair of arcuately preformed resilient means interposed between said last named member and said eccentric on said sleeve to operatively effect their connection, an end disc fitted to said driver shaft to concentrically space said sleeve relative to said driven shaft, and an axially disposed preformed rubber member disposed adjacent said end disc and operatively interposed between said driver and driven shafts to sustain end thrusts therebetween, said last named rubber member and end disc having corresponding notches complementary to 20 said retainer member for aligned registry therewith.

4. In a device of the character described, the combination with a starting driver shaft, a driven shaft telescopically mounted relative to said driver shaft, a pinion fixedly mounted for rotation with said driven shaft to engage and disengage an engine gear for starting purposes, a sleeve telescopically associated with said driven shaft, there being a screw connection between said 35 sleeve and driven shaft, an eccentric formed on said sleeve, a retainer member associated with said driver shaft to circumferentially confront said sleeve eccentric, another sleeve having a longitudinal slit therein to receive said eccentric therethrough to embrace said first named sleeve, and a pair of arcuately preformed resilient rubber means interposed between said last named member and said eccentric on said sleeve to operatively effect their connection.

5. In a device of the character described, the combination with a starting driver shaft, a tubular driven shaft telescopically mounted relative to said driver shaft, a pinion fixedly mounted for rotation with said driven shaft to engage and disengage an engine gear for starting purposes, a sleeve telescopically associated with said driven shaft, there being a screw connection between said sleeve and driven shaft, an eccentric formed on said sleeve, a retainer member associated with said driver shaft for rotation therewith, said retainer having a longitudinal rib disposed in the circumferential path of said sleeve eccentric, another sleeve having a longitudinal slit therein to receive said eccentric therethrough to embrace said first named sleeve, and a pair of arcuately preformed resilient rubber means disposed over said last named sleeve and interposed between said retainer rib and said eccentric on said sleeve to operatively effect their connection.

6. In a device of the character described, the combination with a starting driver shaft, a tubular driven shaft telescopically mounted relative to said driver shaft, a pinion formed integral for rotation with said driven shaft to engage and disengage an engine gear for start-

ing purposes, a sleeve telescopically associated with said driven shaft, there being a screw connection between said sleeve and driven shaft, an eccentric formed on said sleeve, a retainer member associated with said driver shaft for rotation therewith, said retainer having a longitudinal rib disposed in the circumferential path of said sleeve eccentric, another sleeve having a longitudinal slit therein to receive said eccentric therethrough to embrace said first named sleeve, a pair of arcuately preformed resilient rubber means disposed over said last named sleeve and interposed between said retainer rib and said eccentric on said sleeve to operatively effect their connection, and a cylindrical housing surrounding said driving and driven shafts to totally enclose said resilient rubber means.

7. In a device of the character described, the combination with a starting driver shaft, a tubular driven shaft telescopically mounted relative to said driver shaft, a pinion formed integral for rotation with said driven shaft to engage and disengage an engine gear for starting purposes, a sleeve telescopically associated with said driven shaft, there being a screw connection between said sleeve and driven shaft, an eccentric formed on said sleeve, a retainer member associated with said driver shaft for rotation therewith, said retainer having a longitudinal rib disposed in the circumferential path of said sleeve eccentric, another sleeve having

a longitudinal slit therein to receive said eccentric therethrough to embrace said first named sleeve, a pair of arcuately preformed resilient rubber means disposed over said last named sleeve and interposed between said retainer rib and said eccentric on said sleeve to operatively effect their connection, and a cylindrical housing surrounding said shaft and first named sleeve to totally enclose said resilient rubber means.

10 8. In an engine starting device, a starting shaft, a tubular driven shaft surrounding said starting shaft, a radial lug on said driven shaft, a tubular sleeve having a heliculair groove formed therein for telescopic association with said driven shaft, said heliculair groove being in registry with said driven shaft lug to effect axial relative displacement responsive to relative rotation therebetween, said tubular sleeve having an eccentric portion thereon, a retainer member on said starting shaft for rotation therewith, said retainer having a longitudinal rib disposed in the circumferential path of said sleeve eccentric, a pair of arcuate resilient rubber blocks disposed between said eccentric and said retainer rib on opposite sides thereto to render said driven shaft responsive to said starting shaft, and another resilient rubber member axially interposed between said driver and driven shafts to sustain axial end thrusts therebetween.
